FRAME

William I. Adelman, Pittsburgh, Pa.

Application February 27, 1941, Serial No. 380,871

8 Claims. (Cl. 160—382)

My invention relates to a frame and more particularly to frames or sashes for windows and doors. These frames are used to enclose panels of various kinds such as screen cloth, foraminous material, glass and other transparent or translucent materials, and opaque panels of wood or metal, and to improved means for securing the panels in the frame or sash. The frames are formed from plastics of various kinds. By the use of my invention the panel can be securely and permanently locked in desired position, and the locking means and the body of the frame are integral in the finished article.

I also provide a frame formed from plastic having a corner reinforced with a material stronger than plastic, for example, metal.

The plastic material is preferably selected from what is known as "thermoplastics." Materials which are softenable by heat and then workable are suitable and also materials which are thermosetting. The plastic must be rigid and possess reasonable strength at ordinary atmospheric temperature encountered in the use of the frame, and one which has a good and permanent finish or to which a good finish and a permanent finish can be readily imparted. When the article is to be used in exposed locations the material should preferably be highly weather-resistant.

A generally suitable sash or frame can be made from a phenolic resin, such as phenol-formaldehyde resin preferably by molding and even by casting. Amongst other suitable materials which can be used are urea resins, cellulose plastics, acrylic resins, casein plastics, styrene resins, vinyl resins, and lignin plastics. Any color may be used.

Sashes or frames embodying my invention can be expeditiously manufactured at a reasonable price, are long lived, ornamental, strong and highly resistant to deterioration. The panel, be it a reticulated screen or a solid panel, is held in tightly locked engagement in its frame, impervious to the elements.

In the accompanying drawing I have shown for purposes of illustration only certain exemplary embodiments of my invention. In the drawing, which is largely diagrammatic,

Figure 1 is a corner portion of a sash or frame enclosing a screen cloth panel;

Figure 2 is a cross section of the sash along the line 2—2 of Figure 1;

Figure 3 is a cross section of the sash shown in Figure 2, showing one method of fabrication;

Figure 4 is a cross section of another sash;

Figure 4a is a cross section of the sash shown

in Figure 4, showing one method of fabrication:

Figures 5 and 6 are cross sections of still other forms of sash, in the process of being fabricated;

Figures 7, 8, 9 and 10 are cross sections of other forms of frames and associated panels, and Figure 11 is a cross section of a corner of the frame shown in Figure 1, and along the line 11—11 thereof.

In Figures 1 and 2 of the drawing I show a portion of a sash or frame 10 having a vertical stile 11 and a horizontal rail 12, each formed from a suitable thermoplastic, surrounding the edges of an area of screen cloth or wire 13. The sash as shown is substantially rectangular in cross section and the edge of the wire screen is firmly embedded in the material of the sash as shown in Figure 2. The screen can be embedded by first forming the plastic sash with an upstanding lip 14 and a flat ledge 15 (see Figure 3) on which the edge of the wire screening 13 is placed. The sash and wire are assembled in a suitable mold 16, and the plastic softened by heat, after which the lip 14 is turned down to contact the ledge 15 and embed the edge of the wire screen 13 to form the sash, a cross section of a portion of which is shown in Figure 2. The same structure can also be made by making the sash in two pieces or horizontal layers as in Figure 8 and welding the two layers together with the wire screen in between the layers. The welding can be done by heating and pressing or where layers are used the layers may be united by solvent welding. So also the plastic could be molded around the edge of the screen wire by casting.

In Figure 4 there is shown the cross section of a plastic sash in which the edge 17 of the screen cloth 18 is kinked and embedded in the sash. This form can conveniently be made by preforming the plastic in two complementary pieces 19 and 20. The main piece 20 has a ledged groove 21 into which the edge of the screen cloth 18 is received, the construction being such that the screen cloth is stretched over an outside lip 22 and the edges 17 forced into the groove 21. The small piece or fillet 19, having surfaces which are complementary to the main piece 20, is then pressed into heated engagement with the main piece and the pieces fused together to form the structure shown in Figure 4. As shown in Figure 5 the fillet used in Figure 4a may be omitted and the screen 23, after being stretched and positioned is pressed into heated engagement with the main piece forming the grooved sash 24 and embedded therein.

The sash 25 shown in Figure 6 has a ledge portion 26 into which the edge of the wire screen 27 is embedded by pressing and heating, so that the surface of the ledge and the upper surface of the screen are in substantially the same plane.

I show in Figure 7 a sash or frame 28 having a ledge portion 29 the upper surface of which engages the lower edge of a panel 30 which may be glass, metal, plastic, wood, screen cloth or other desired material. The upper edge of the panel is engaged by a fillet or strip 31 of thermoplastic material one edge of which engages the sash. The fillet 31 is then heated and pressed into engagement with the sash and fused thereto to form an integral sash which grips the edge of the panel 30.

In Figure 8, the sash comprises a lower portion 32 and a cooperating upper portion 33 having beveled mating surfaces 34 and an edge groove 35, in which the edge of panel 36 is received.

The construction shown in Figure 9 is similar to that described and shown in Figure 8 except that the mating surfaces of the pieces 37 and 38 are not beveled. So also the construction illustrated in Figure 10 is similar to the construction shown in Figure 9, except the pieces 39 and 40 have a T-shaped groove 41 when assembled. In this groove a readily deformable filling material can be placed to seal the edge of the panel 42. A suitable material for the filler is ordinary putty, cement, and partially cured soft rubber.

While I have indicated mating surfaces in Figures 7, 8, 9, and 10, by means of lines and have differently cross hatched the cooperating pieces which comprise the sash, it will be understood that the sash when completed forms an integral whole without apparent cleavage lines. It is also within my contemplation to join the pieces or parts by welding them, for example, by the use of a suitable solvent. It may be noted that the union of the parts is effected by a chemical fusion produced by the solvent, and it may further be noted that the term "welding" applies not only to the union effected through the use of solvent, but also to the union effected by the use of heat.

In Figure 11, I have shown a cross section of a desirable corner construction for joining the side member or stile 11 and the end member or rail 12 of a frame. The ends of each are reduced in cross section and a metal reinforcing plate 43 having holes 44 therein is placed between the mating surfaces at the corner. Sufficient thermoplastic stock is provided so that when the ends are fused together by pressure and heat the surfaces and edges will all be flush. This operation can be performed at the same time that the screen or panel is being fused into position in the sash.

A frame or sash, made according to my invention, tightly and permanently grips the associated panel and provides weather-tight joints and a structure having a long life, permanently colored, and of pleasing appearance. The frame can be cheaply and quickly made, and there is no possibility of any portion working loose.

While I have described certain exemplary embodiments of my invention, it is to be understood that various changes in the arrangement and shape of the frame and the methods of making it may be made within the scope of my claims.

I claim:

1. A structure of the class described comprising a panel of screen cloth having its edges offset from the plane of the panel body, and a surrounding rigid one-piece frame of organic fused and shaped thermoplastic material embedding and rigidly solidified upon such edges of the screen cloth and filling the interstices in the embedded edges.

10 2. A structure of the class described comprising a panel of wire screen and an integral rigid one-piece supporting frame of thermoplastic organic material, said frame having a ledge portion, said ledge being fused and rigidly solidified upon and embedding the edges of the wire screen.

15 3. In a window comprising a panel and a surrounding frame, a rigid one-piece frame made from sections of thermoplastic organic material fused and rigidly united to form an edge groove in which the panel is marginally received and a sealing groove forming an extension of the edge groove and enclosing a seal in contact with the rim of the panel.

20 4. A structure of the class described comprising a panel of wire screen and an integral supporting frame having a peripherally extending ledged groove in which and over the ledge of which the edges of the wire screen lie, said frame being formed of thermoplastic material fused and rigidly solidified upon said edges of the screen and within the interstices therein.

25 5. A structure of the class described comprising a panel of wire screen and an integral supporting frame having a peripherally extending ledged groove in which and over the ledge of which the edges of the wire screen lie, said frame being formed of thermoplastic material fused and rigidly solidified upon said edges of the screen and within the interstices therein, the plane of the panel being approximately coincident with the plane of one of the faces of the frame body.

30 6. A structure of the class described comprising a frame having a side member and an end member formed of plastic material, and a corner reinforcing element formed of a different material, said members being at a corner of the frame, fused and rigidly united, with said reinforcing element embedded in and integrated with the solidified plastic material of the frame members.

35 7. A structure of the class described comprising a frame having a side member and an end member formed of plastic material, and a perforate corner reinforcing element formed of metal, said members being at a corner of the frame, fused and rigidly united with each other and with said perforate reinforcing element, the fused and solidified plastic material filling the perforations in the reinforcing element.

40 8. A structure of the class described comprising a panel and a surrounding integral frame formed of a plastic material fused upon the edges of the panel and rigidly solidified, with said edges embedded in the plastic material of the frame, said frame having a side member, an end member, and a perforate corner reinforcing element, said members being at a corner of the frame, fused and rigidly united with each other and with said perforate reinforcing element, the fused and solidified plastic material filling the perforations in the reinforcing element.

70

WILLIAM I. ADELMAN.
